(57) **CLAIM**

The ornamental design for a dog bone topical dispenser, as shown and described.

DESCRIPTION

The dog bone topical dispenser is intended for use as a dispenser of a formulation such as a solid, semi-solid or fluid formulation. One example of such a formulation is a formulation intended for tick and flea control on pets, and in particular dogs.

FIG. 1 is a perspective view showing a dog bone topical dispenser; and,

FIG. 2 is another a perspective view showing four (4) dog bone topical dispensers arranged side by side in a single package.
